LIQUID KNOCKOUT APPARATUS

Asbury S. Parks, Houston, Tex.

Application March 13, 1950, Serial No. 149,375

11 Claims. (Cl. 210—52)

1

This invention relates to new and useful improvements in liquid knockout apparatus.

This application is filed as an improvement on the apparatus disclosed in my co-pending application, Serial No. 46,598, filed August 28, 1948.

The invention relates particularly to high pressure liquid knockout apparatus wherein free water or liquid hydrocarbons are separated from a high pressure gas or distillate. The invention will be described herein as separating water from gas or distillate but it is to be understood that it may be employed for separating any liquids.

In my co-pending application above referred to, it is pointed out that the freezing problems which are encountered in high pressure gas lines are due to the gas-water hydrates and that if removal of substantially all of the water can be successfully effected, these difficulties are overcome. Since water must be present in a liquid state in contact with the gas in order for gas-hydrates to form, maintenance of the gaseous stream at a temperature above dew point conditions where no liquid water exists will prevent formation of hydrates. If the free water is removed at the point of highest pressure in the system and the temperature is not thereafter further lowered to the point of further condensation no hydrates will subsequently be formed.

The apparatus disclosed in my co-pending application effectively accomplishes the required removal of water under high pressure but the particular apparatus has certain structural disadvantages. For instance, the liquid accumulating chamber is illustrated as suspended from the flow line with the controls for the apparatus being supported by a structural frame and it has been found that atmospheric temperature changes which cause expansion and contraction of the line and of the supporting structure result in deflections of the liquid accumulating chamber or movements of the controls of the apparatus which erroneously operate said controls to cause erroneous operation of the apparatus. Also, said apparatus includes a restriction or choke in the main gas line to effect a return of the hydrocarbon liquids from the accumulating chamber back into said line and such restriction may be undesirable under certain conditions. In addition the prior apparatus has other features which although not interfering with the ultimate efficient results obtained by said apparatus, are not too desirable from an economical standpoint.

It is therefore one object of this invention to provide a liquid knockout apparatus having all of the advantages of the apparatus shown in my

2

co-pending application, Serial No. 46,598, filed August 28, 1948, and in addition having certain improvements thereover which assure more efficient and reliable operation of the apparatus.

5 An important object of the invention is to provide a high pressure separating apparatus having improved control means for controlling the dumping or escape of the separated liquid, which means does not employ a float or float-controlled escape valve, whereby the inherent disadvantages of a float in high pressure vessels, together with the sealing problems incidental thereto, are eliminated and more sensitive operation is accomplished.

10 15 Still another object of the invention is to provide an improved separating or knockout apparatus which entirely eliminates a float mechanism and which utilizes the weight of the separated liquid as the controlling factor in actuating the

20 25 liquid escape or dump valve, whereby the liquid accumulation vessel may be of a relatively small size and also whereby the overall construction of the unit may be made more rugged to withstand the high pressures encountered without sacrificing sensitivity in operation.

Another important object of the invention is to provide an improved liquid knockout apparatus wherein the liquid accumulating chamber as well as the control devices therefor are all mounted on the same supporting structure whereby any expansion or contraction of the structure does not cause a change in the relative positions of said chamber and control devices and therefore, does not affect the efficient operation of the apparatus.

30 35 Another object is to provide an improved liquid knockout apparatus, of the character described, wherein the liquid accumulating chamber and the various control devices of the apparatus are suspended from the gas flow line and, in effect, form a part thereof whereby the chamber and controls are maintained in the same positions with respect to each other irrespective of expansion and contraction of the flow line as caused by atmospheric temperature changes.

40 45 A particular object is to provide an improved liquid knockout apparatus, of the character described, having means for returning the hydrocarbon liquid from the accumulating chamber back to the gas flow line without the necessity of locating a restriction in said line.

50 55 A further object is to provide an apparatus of the character described wherein the separating vessel is entirely independent of the accumulating vessel and control devices and is connected there-

to by the gas flow line, whereby said flow line forms the sole support for the complete apparatus.

A still further object is to arrange the connection between the gas flow line and the liquid accumulating vessel in a manner to cause the flowing gas stream to function to automatically draw the hydrocarbon liquid back into said line from the liquid accumulating chamber; the arrangement also assuring the maintenance of a predetermined constant hydrocarbon liquid level whereby control of the apparatus is solely in accordance with the rise and fall in the level of the water in the accumulating vessel.

Other and further objects of this invention will appear from the following description.

In the accompanying drawings which form a part of the instant specification, are to be read in conjunction therewith, and wherein an example of the invention is shown:

Figure 1 is an isometric view, with portions in section, of a liquid knockout apparatus constructed in accordance with the invention.

Figure 2 is a side elevation thereof, viewing the apparatus from the side opposite that of Figure 1.

Figure 3 is a longitudinal sectional view of the apparatus.

Figure 4 is a horizontal cross-sectional view, taken on the line 4—4 of Figure 3.

Figure 5 is an end elevation.

Figure 6 is an enlarged sectional view of the pilot pressure control device which is actuated by deflections of the liquid accumulating vessel.

Figure 7 is a view, partly in section and partly in elevation, of the motor valve which controls dumping of the liquid from the liquid accumulating chamber, and

Figure 8 is a sectional view of the regulator which controls the flow of a portion of the gas from the high pressure flow line to the pilot supply line.

In the drawings, the numeral 10 designates a high pressure flow line through which a high pressure gas stream is conducted. The line 10 may extend from the well head of a high pressure gas or distillate well or may extend from any other source of high pressure fluid. The flow stream within the line 10 may consist of gas, hydrocarbon liquid and water, and said stream is directed into a suitable horizontal separator or scrubber 11. The separator functions to separate the gas from the free liquids in the flow stream and the separated gas flows from the separator through a down pipe 13. The pipe 13 extends downwardly in a plane below the separator and has connection with a lateral or horizontal pipe section 14 which is connected to a T 15 from which an upwardly projecting pipe leg 16 extends. The upper end of the leg is connected through a turn or elbow 17 with the flow pipe 19a, which pipe forms a part of the flow line. It will be evident that the down pipe 13, the lateral portion 14 and the upstanding leg 16 actually form a downwardly directed offset in the flow line which is formed by the pipes 13 and 19a.

The flow stream enters the horizontal separator and the separated gas, upon leaving said separator, escapes through the offset formed by the pipes 13, 14 and 16 and then passes downstream through the pipe 19a. The liquids which are separated within the horizontal separator or scrubber 11 are conducted therefrom through a conductor 18. This conductor has a vertical

portion 18a which has its upper end welded or otherwise secured to the shell of the separator 11. The conductor also includes an elongate lateral or horizontal portion 18b which has connection 5 with a curved conduit 19. As is clearly shown in Figure 5, the conduit has an upper leg 19a and a lower leg 19b, with the latter connected to and supported by a T member 20. A blank or plug 19c is disposed within the leg 19b to prevent flow 10 from the curved conduit 19 to the T member 20. A short nipple 21 also connected in the T extends through an opening 22 provided in one end of a liquid receiving and accumulating vessel 23 and said nipple is securely welded or otherwise 15 secured to the vessel. Suitable braces 24 which extend between the T and the vessel further secure the T firmly to the vessel.

An inclined pipe 25 has its upper end connected to and in communication with the lower leg 19b 20 of the curved conduit 19 in advance of the plug 19c (Figure 5) while its lower end is connected with the opposite end of the liquid-accumulating vessel 23. With this arrangement it will be obvious that liquid separated in the horizontal separating chamber 11 may flow downwardly through the conductor 18, then through the curved conduit 19 and then through the inclined pipe 25 to the interior of the vessel 23.

The T 20 by which the end of the curved conduit 19 is supported is also connected with a second curved conduit 26 which includes an upper leg 26a and a lower leg 26b. The bore of the lower leg communicates with the T 20 while the upper leg has connection with the T member 15 35 provided in the offset portion of the main flow line. The upper leg 26a of the conduit 26 is in the same horizontal plane as the upper leg 19a of the conduit 19 and the legs 26a and 19a also lie in the same horizontal plane as the lateral portion 18b of the conductor 18, as well as the lateral section 14 of the offset portion in the flow line.

As has been noted the flow stream may contain hydrocarbon liquid and also free water, and these liquids are separated by the separator 11 and are conducted downwardly through the conductor 18 and inclined pipe 25 to the interior of the vessel 23. Within the interior of the vessel the free water, being heavier than the hydrocarbon liquid, will settle to the bottom while the hydrocarbon liquid will rise toward the top of the vessel. Because the curved conduit 26 is in direct communication with the interior of the vessel 23 it will be evident that the hydrocarbon liquid will rise upwardly within this conduit and will enter the upper leg 26a of the conduit. The gas which has been separated in the separator 11 is, of course, flowing downwardly through the offset portion of the flow line, which offset, as 45 has been explained, is formed by the down pipe 13, lateral 14 and upstanding pipe 16. As the gas makes its turn through the T 15 and flows upwardly in the upstanding pipe 16, any liquid in lateral 14 is swept up with the gas so that 50 the flowing gas functions to draw the liquid back into the flow line. In actual practice, the level of the hydrocarbon liquid will be at the point L (Figure 5) in the conductor and in the lateral leg 26a because at any time that the level rises above this point the flowing gas will function to draw the liquid into the main flow line. The arrangement of the conductor 18 and conduit 26 with respect to the vessel 23 thus provides a means whereby the hydrocarbon liquids which 55 are separated in the separator 11 are brought

back into the main flow line without the necessity of forming any restriction or pressure drop in said line. Further, the arrangement of these conductors provides for an accurate control of the hydrocarbon liquid level, with the result that any variation in the weight of the liquid accumulating vessel 23 will be the result of a variation of the level of the water within the lower end of said vessel.

The vessel 23 comprises a cylindrical shell having its ends closed by end members 27 which are welded or otherwise permanently secured in place to withstand extremely high pressure. The T 20 to which the curved conduits 19 and 26 are attached is welded or otherwise rigidly secured to one end of the vessel 23 and conductors 18 and 14 together with the conduits 19 and 26 form the sole support for the vessel. It may therefore be said that the vessel is in fact suspended from the main flow line with the separator 11 forming a part of said line. For supporting the separator and the main flow line, a suitable frame 28 may be provided and such frame has the separator 11 rigidly fastened thereto. Any expansion or contraction of the supporting frame 28 which may be caused by atmospheric temperature variations will effect the main flow line and since the vessel 23 is carried or suspended from the line the relative position of the vessel with respect to its supporting conductors will remain the same. Also, any variations in the main line will not cause a change in the relative position of the vessel with respect to the line. To assure rigidity of the offset portion of the flow line formed by the members 13, 14 and 16, the supporting frame 28 may be welded or otherwise secured by a brace 29 to the turn 17 which connects the offset portion to the pipe 10a of the main flow line.

By mounting the vessel 23 in the manner illustrated and by controlling the level of the hydrocarbon liquid, it is apparent that any change in the weight of the vessel 23 will be a result of a change in the level W of the water within said vessel. If the volume of water within the vessel increases to raise the water level W it will be evident that the overall weight of the vessel 23 will be increased. Such increase in weight will tend to deflect the vessel and its rigid supporting structure downwardly, and the tendency toward downward deflection will be greatest at the free end of the vessel, that is, at the end opposite the point of attachment of the supporting T 20. When a predetermined water level W occurs within the vessel it is desirable to discharge some of the water and for this purpose a discharge valve 30 (Figure 2) is provided. This discharge valve is illustrated as a motor valve and has connection through an angular line 31 with a withdrawal pipe 32 which extends downwardly within the vessel 23. A suitable hand valve 33 may be connected in the line 31 to permit manual withdrawal of water from the vessel, provided, of course, that the discharge valve 30 is open. A suitable discharge line 34 extends from the valve 30 and it will be evident that when the valve is opened water from the lower end of the vessel may be withdrawn through said discharge line.

It is apparent that the discharge or dump valve 30 is to be opened when the water level within the vessel rises to a predetermined height and said valve must be closed when the water level has been lowered a predetermined amount. Closing of the valve occurs before all of the water

is removed from the vessel in order to prevent the escape of any of the hydrocarbon liquids which accumulate in the vessel above the water therein. In the present apparatus the deflection 5 of the supporting structure of the vessel is utilized to control the operation of the discharge valve and manifestly this deflection will be in direct proportion to the volume of water which accumulates within said vessel. The weight of 10 the water accumulating in the vessel will cause a downward deflection of the supporting structure with a resultant movement of the vessel which will tend to move the outer free end of said vessel in a downward direction. This tendency of the outer free end of the vessel to move in a downward direction upon increase of the weight will represent a downward force which, as will be explained, is utilized to control operation of the discharge or dump valve 30. Operation 15 of the motor valve 30 is effected by means of a pilot pressure fluid and as illustrated, the source of this pilot pressure fluid may be the high pressure main flow line 10. A portion of the high pressure gas flowing through said line 20 is conducted from the lateral leg 14 of the offset portion of said line through a regulator A which functions to reduce the high pressure gas to a desired lower pressure. A pilot pressure fluid line 35 extends from the regulator A to a drip pot 36; from the drip pot the pressure is conducted through an ordinary regulator 37 which accurately controls the pressure of the pilot fluid and then through a line 38 to a control unit B. The control unit is mounted on a supporting plate 30 which overlies the free end of the vessel 23 (Figure 3) and the supporting plate is secured to the offset portion of the main flow line, being welded or otherwise rigidly fastened to the lateral 35 14 of said offset portion. It will be evident that 40 since the supporting plate 39 which carries the control unit B is fastened to the flow line any movement of said line due to expansion and contraction will not change the relative position of the control unit B with respect to the vessel because both the unit and the vessel are carried or supported by the line.

The pilot control unit B has an operating stem 40 at its upper end which is arranged to be engaged by an adjustable screw 40a mounted in a transversely extending bar 41 which is carried 45 50 by a supporting angle member 42, said bar being located in overlying relationship to the unit B. The pilot pressure fluid from the line 38 passes through the pilot control unit B and is then conducted through a line 44 to the motor valve 30. It is thus obvious that the pilot control unit actually controls the application of pilot fluid pressure to the motor operated discharge or dump valve 30 whereby said discharge valve is opened 55 and closed. The provision of the adjustable screw 40a permits an adjustment of the screw and its bar 41 relative to the stem 40, whereby a control of the liquid level in the vessel may be had.

60 65 By observing Figure 3 it will be apparent that the vessel 23 is suspended at one end from the conductor 18 and the offset portion of the main flow line whereby the free end of the vessel will have a tendency to deflect downwardly upon an increase in weight of the vessel and will tend to return to a normal upward position upon a decrease in such weight. Through the angle member 42, bar 41 and screw 40a, a portion of the weight of the vessel is imposed upon the operating 70 75 stem 40 of the control unit B and thus the

force which is applied to the operating stem of the control unit is variable in accordance with the weight of the vessel 23 and its contents. As will be explained, a predetermined application of force to the operating stem will result in building up a pressure within the pilot control unit B and upon reaching a predetermined pilot pressure the control unit B operates to apply full pilot pressure to the diaphragm 45 of the motor valve, whereby said valve is opened to discharge water from the vessel. Similarly, as water discharges through the open valve 39 the weight of the vessel is reduced and the force applied to the operating stem 49 of the control unit is accordingly reduced, whereby the control unit functions to shut off the application of pressure to the motor valve diaphragm and to release the pressure acting thereon to cause said motor valve to immediately close.

From the foregoing it will be seen that the water is permitted to accumulate in the vessel or tank 23 until a sufficient force has been applied to the operating stem 49 of the control unit to build up a predetermined pilot pressure in said unit. When such predetermined pressure, which is representative of liquid level, is reached, full pilot pressure is directed through the line 44 to the motor valve to operate the same with a snap action; similarly, when the force applied to the operating stem 49 is decreased to a certain point, pressure to the motor valve is shut off and is released to allow the motor valve to close with a snap action. It is pointed out that the actual movement of the vessel 23 is very slight and in actual operation as the vessel tends to move downwardly due to increased weight, the control unit functions to balance the applied force to substantially retain the vessel in its initial position. This action of the pilot control unit, as will be explained, increases pilot pressure but the net resultant motion of the vessel 23 is zero. As additional force is applied to the operating stem due to increased weight on the vessel the operation is repeated, that is, the control unit B balances the applied force to further increase pilot pressure. In this manner, the vessel undergoes substantially no motion and it is therefore possible to mount said vessel rigidly by means of welded or other permanent connections to assure efficient operation, without leakage or friction under extremely high pressures.

In order to dampen the movement of the free end of the vessel so as to prevent chattering a dashpot 43 (Figure 1) is mounted on the supporting plate 39 and has its operating rod 47 engaging the under side of the bar 41 which is attached to the supporting angle member 42. The dashpot prevents harmonic vibration of the free end of the vessel 23. A suitable gauge glass 48 is connected with a pipe 49 extending from the upper portion of the vessel and also with a pipe 50 connected to the lower end of the vessel. The pipe 49 is below the liquid level within the vessel. An additional discharge line 51 connects with the pipe 50 and has a suitable hand valve 52 mounted therein whereby an auxiliary manual discharge of the contents of the vessel may be had.

The various elements, such as the regulator, A, the pilot control unit B and the motor valve 39 are subject to some variation in construction since various types of these particular devices could be employed. The pilot control unit B must, however, be constructed so as to be extremely sensitive to a very small deflections of the

vessel or tank 23. The preferred form of units which are employed are illustrated in Figures 6 to 8 and each unit will be briefly described.

Referring to Figure 8, the regulator A is shown. As has been stated the particular regulator A makes it possible to employ the high pressure flow line 10 as the source of the pilot pressure fluid. It is to be remembered that the gas within the line 10 is of relatively high pressure, probably of the order of 2000 pounds per square inch or higher. To reduce a portion of this fluid to a relatively low pilot pressure in the order of 50 pounds presents a freezing problem and the regulator A is especially designed to allow a portion of the extremely high pressure flow stream to be taken therefrom and its pressure reduced without danger of freezing. Where an outside source of low pressure pilot gas is available the regulator A may be omitted, but in most instances, such a source of low pressure gas is not readily obtainable and the regulator A permits the pilot gas to be taken from the high pressure line 10.

The regulator A includes a body portion 53 which may be constructed of various sections with an internal chamber 54 being formed within said body. An operating diaphragm 55 closes the upper end of the chamber and an adjustable coil spring 56 exerts a predetermined pressure on the diaphragm. The diaphragm has a depending flanged stem 57 connected thereto and this stem is connected through an ordinary reverse motion assembly 58 with a valve control rod 59. The lower end of the rod engages a ball valve 60 to urge the same into engagement with a seat 61 at the upper end of a restricted orifice 62. The valve 60 and its seat 61 are disposed within an outer casing 63 which is located wholly or entirely within the flow stream passing through the lateral leg 14 of the offset portion of the main flow line 10.

It will be evident that when the pilot valve 60 is opened, the pressure reduction is at the seat 61 and this is the point where normal freezing might occur. However, because of the location of the valve and the fact that only a very small volume of gas is taken from the main gas stream the temperature of the large volume of the main gaseous stream is sufficient to overcome or counteract the cooling effect whereby no freezing occurs. The pilot line 38 has one end connected with the chamber 54 and so long as the pressure within said chamber is at the desired pressure as determined by the adjustment of the spring 56 the diaphragm 55 is held in its upper position which through the reversing mechanism applies a downward force to the operating rod 59 and holds the valve 60 seated. Any reduction in pressure in the chamber 54 permits the spring 56 to urge the diaphragm downwardly and through the reversing mechanism 58 reduce the applied force on the rod 59, whereby the pilot valve 60 may be unseated to admit additional pressure into the chamber 54. Upon this pressure again building up to a predetermined point the valve 60 is again seated.

As has been pointed out the particular regulator A makes it possible to employ the high pressure fluid as the source of the pilot pressure fluid without danger of freezing of the regulator and this eliminates the necessity of providing a separate source of pilot pressure fluid. It might be noted that the regulator shown in Figure 8 is fully described and claimed in my co-pending application, Serial No. 37,183, filed July 6, 1948.

The pilot pressure fluid is conducted from the regulator A through the line 35, drip pot 36, regulator 37 and line 38 to the pilot control unit B which is clearly shown in Figure 6. The ordinary regulator 37 merely functions to steady and further reduce the pressure flowing to the control unit, if such further pressure reduction is required. The control unit B is in effect a combined control and snap action device and comprises an upper casing section 64 having an inlet opening 65 at one side thereof, said opening having the pilot pressure line 38 connected thereto. The opening 65 communicates with a chamber 66 located axially within the lower portion of the casing or housing 64. An axial bore 67 extends upwardly from the chamber 66 and has a valve seat member 68 provided with an axial valve seat 69 threaded therein. The member 68 is formed with an axial bore 70 extending therethrough whereby flow from the pilot supply line 38 may enter the chamber 66 and then flow upwardly past the valve seat 69 into the chamber 71 in the upper portion of the bore 67 of the casing. A valve 72 is adapted to engage the seat 69 and has a valve stem 73 projecting upwardly therefrom; the upper end of the valve stem is threaded into the depending shank 74 of a tubular element 75. A diaphragm 76 spans the upper end of the bore 67 of the casing and the outer periphery thereof is clamped between the upper end of the casing and a locking ring 77. The diaphragm 76 has a central opening through which the shank 74 extends and a clamping nut 78 clamps the under side of the diaphragm to the element.

The operating stem 40 of the unit B is hollowed out and has its lower edge engaging the upper edge of the tubular element 75 which carries the valve 72. The interior of the stem or operating member 40 and the enlarged upper portion of the bore of the tubular element 75 form a chamber 79 which has communication with the area below the diaphragm 76 through a vertically extending passage 80. The stem or operating member 40 is flanged and may undergo limited upward movement with respect to the tubular element 75 but is confined against complete upward displacement by a retaining cap 81 which is threaded onto the upper end of the casing 64. The area of the chamber 71 below the diaphragm but above the valve seat communicates through an inclined passage 82 with an opening 83 formed in the casing. A U-shaped conductor 84 has its upper end threaded into the opening 83 and will function to conduct pressure fluid from the chamber 71.

An intermediate section or body 85 is secured to the lower end of the casing 64 and a base section 86 is fastened to the lower end of the intermediate body. The body 85 has an axial bore 87 which is enlarged at its lower end to form a chamber 88. A valve assembly is mounted within the intermediate section and comprises an upper valve disc 89 having an annular valve seating ring 90 and a lower valve disc 91 having an annular valve seating ring 92, the discs being connected by a shank 93 which extends through the bore 87. The upper valve 89 is disposed in the chamber 66 in the lower portion of the casing 64 and has its valve ring adapted to engage a flexible seat 94 provided on the upper end of the intermediate body 85. The lower valve has its valve ring 92 adapted to engage a flexible seat 95 provided at the intersection of the bore 87 and the chamber 88.

A diaphragm 96 closes the lower end of the chamber 88 and is confined between the body 85 and

and the base 86. The central portion of the base is formed with a chamber 97 below the diaphragm 96 and an inlet port 98 communicates with the chamber. The conductor 84 which leads from the chamber 71 in the upper casing 64 has its lower end connected in the port 98 so that the pressure fluid from chamber 71 may be conducted to the chamber 97 below the diaphragm 96. Opposite the inlet port 98 the base is formed with an outlet 99 which is normally closed by a plug 100. As will be pointed out this opening may be utilized when it is desired to actuate the motor valve with a throttling action but where snap action is required, the plug closes said opening.

The intermediate body or section 85 is formed with a radial outlet port 101 which has the pressure line 44 connected thereto. Extending through the wall of the body and from the chamber 88 is a bleed or relief port 102 and when the valve discs are in a lowered position, as shown in Figure 6, pressure fluid within the line 44 may be relieved through the bore 87, chamber 88 and relief port 102.

25 The diameter or area of the valve 90 at its seating position is of greater cross-sectional area than the diameter of the valve 92 at its point of seating and the length of the connecting shank 93 is such that when one of the valves is seated 30 the other is unseated. The lower end of the chamber 88 is, of course, closed by the flexible diaphragm 96 and the effective cross-sectional area of said diaphragm is greater than the effective seating area of the upper valve 90. The diaphragm 96 actually functions as the top of the chamber 97 in the base 86 and is, therefore, exposed to the pressure within said chamber.

35 With the motor valve 30 to be operated with a snap action the plug 100 closes the port 99 in the 40 base and the line 44 is connected in the port 101 of the unit B. The constant supply pilot pressure from line 38 is present within the chamber 66 and is acting on the effective cross-sectional area of the upper valve 90 to hold this valve 45 downwardly in a seated position. As the force applied on the operating member or stem 40 of the unit is increased due to an increase in weight of the vessel 23, the valve 72 is moved toward an open position and the pilot pressure is permitted to flow into the chamber 71. Immediately that the pressure enters the chamber 71 it acts upon the diaphragm 76 to immediately balance the applied force and return the operating stem to its initial position with the valve 72 closed. Thus, a 50 certain pressure is present in the chamber 71 but this pressure is less than the full pilot pressure. As additional liquid accumulates in the vessel 23 and an increased force is again applied to the stem 40 the valve 72 is again momentarily opened and additional pressure is admitted to chamber 71. This pressure is present within passage 82 and conductor 84 and within the bore 87 below the diaphragm 96. Obviously, until such time as the pressure within chamber 71 and the chamber 55 97 reaches a predetermined point the full pilot pressure which is acting on the upper valve 89 will hold said valve in a seated position. The relationship between the cross-sectional area of the diaphragm 96 to the valve 89 will control the point to which the pressure must be built up in chamber 97 before the valve discs 89 and 91 are moved upwardly.

60 It will be evident that through the valve 72 the pressure in chambers 71 and 97 is modulated or controlled in accordance with the force being

applied to the operating stem 40 and when this pressure has built up to the predetermined point for which the device is constructed the pressure in chamber 97 is sufficient to move the valve discs upwardly; at this point unseating of the valve 90 will admit full pilot pressure to the bore 87 and to the line 44 leading to the motor valve. Thus, full pilot pressure is applied to the motor valve to open the same with a snap action. At the instant that the pressure in the chamber 97 acting against the diaphragm 96 overcomes the constant supply pressure acting to hold the valve discs downwardly both valve discs are snapped upwardly and the action is so rapid due to the sudden release of force holding the valve assembly down that the lower valve 92 moves into engagement with its seat 95 before the pilot pressure can fill the volume of the bore 87 between the upper and lower valve discs. As has been noted, the area of the valve 92 is less than the area of the valve 90 and thus, the pilot supply pressure which is tending to move the valve downwardly off of its seat is acting on the lesser area of the valve 92. Because the effective area of the diaphragm 96 is considerably larger than the area of the lower valve said lower valve will be held seated against the full pilot pressure and the motor operated discharge valve 30 is thus snapped to an open position.

When the valve opens and liquid is conducted from the vessel a reduction in the applied force to the pilot operating member occurs and as this force reduces sufficiently the pressure in the chamber 79 formed between the operating stem 40 and the tubular element 75 allows these parts to separate to permit venting of the pressures within the chambers 71 and 97. When this pressure in these chambers has reduced to a point where the full pilot pressure acting on the lower valve 92 can unseat said valve, the lower valve begins to move downwardly. As the lower valve 92 begins to leave its seat there is a momentary leakage of pilot gas past this seat outwardly from the relief port 102 and since the diameter of this opening is relatively small a back pressure is built up within the chamber 88 above the diaphragm 96. This back pressure immediately acts on the top side of the diaphragm 96 and causes the diaphragm to remove all resistance to the lowering of the valve disc assembly and the full pilot pressure in chamber 66 then seats the upper valve. The pressure which functions to open the motor valve 30 may then bleed outwardly through the bore 87, chamber 88 and vent opening 102. The parts will remain in this position until the applied force again builds up the modulated pressure within the chambers 71 and 97 at which time the operation is repeated.

If it is desired to operate the motor valve with a throttling action the line 44 leading to said motor valve is connected within the port 99 while the plug 100 closes the port 101. In such case, it will be evident that the pressures in the chambers 71 and 97 will control the position of the motor valve. It might be noted that the unit B is a combined control and snap action unit and is fully disclosed in my co-pending application, Serial No. 105,203, filed July 16, 1949. It is not necessary that the snap action control be incorporated with the modulated pressure control since the snap action device could be a separate unit.

The particular motor valve which is employed is, of course, subject to variation but as illustrated includes the operating diaphragms 45

which has connection with a valve stem 103 having a valve element 104 at its lower end. A coil spring 105 resists movement of the diaphragm 45 and maintains the valve 104 in a closed position. When a pressure is applied beneath the diaphragm the valve 104 is opened to permit flow through the discharge line 34.

In the operation of the apparatus, the vessel 23 receives the separated liquids from the flow line 10, such separation being effected by the separator 11. The liquids flow downwardly through the curved conduit 19 and inclined pipe 25 into the vessel. These liquids may be water and hydrocarbon liquids and obviously the water will settle to the lower portion of the vessel.

The gas which will be separated in the separator 11 flows downwardly through the offset portion formed by the down pipe 13, lateral 14 and upstanding pipe 16 in the main flow line, and then continues down the line through the main flow pipe 10a. The upper portion of the vessel 23 is in communication with the offset portion of the main flow line through the curved conduit 26 and thus the hydrocarbon liquids which rise above the water in the vessel may pass upwardly through the curved conduit. The upper end of the conduit 26 is disposed in the same plane as the lateral 14 of the offset portion of the flow line and upon the hydrocarbon liquids reaching this level a siphon effect is produced whereby the flowing gas stream functions to withdraw the hydrocarbon liquids back into the main line. In addition this construction provides for maintaining the level of the hydrocarbon liquids constant so that any variation in the weight of the vessel 23 will be due to a variation in water level W within said vessel.

The vessel is rigidly supported at one end so that as the weight thereof increases its free end tends to move downwardly. This free end is applying a force to the control unit B and as has been explained, as the vessel 23 tends to move downwardly because of increased weight an increased force is applied to the operating stem 40 of the control unit. Immediately that this force is applied the control unit is actuated to increase the modulated pressure and this pressure balances the applied force to maintain the vessel in substantially its initial position. Thus, the modulated pressure is increased in the chambers 71 and 97 of the control unit B while the net resultant motion of the vessel is zero.

As the water level in the vessel rises the applied force increases and the modulated pressure tends to increase accordingly and when this pressure reaches a predetermined point, full pilot pressure is applied to the motor valve 30 to open said valve and discharge water. The discharge of water from the vessel reduces the overall weight of said vessel and also reduces the applied force to the unit B. Decrease in applied force results in decrease of modulated pressure to the point where the pressure acting on the motor valve is relieved to close said motor valve 30. It is thus obvious that the apparatus provides a unit wherein the weight of the liquid accumulating vessel is utilized to control the operation of the discharge valve and this control is accomplished with substantially zero motion of the vessel. This means that the vessel may be rigidly mounted so that all joints may be permanently welded to withstand the excessively high pressures. Actually the entire vessel functions as a float and therefore extremely sensitive operation is produced. No internal float

mechanism with its inherent disadvantages is required.

The apparatus provides an arrangement whereby the flowing gas stream is utilized to return the separated hydrocarbon liquids into the main flow line without the necessity of providing restrictions or chokes which create pressure drops in said main flow line. Also, the vessel and the control devices are all supported from the main flow lines with the result that any movement of the line due to expansion and contraction because of atmospheric temperature changes will not change the relative position of the control unit with respect to the vessel. With this arrangement an accurate and sensitive control is had because the only variation which occurs between the relative position of the vessel to the pilot control unit is due solely to a change in weight of the vessel and its contents. Although the separator has been illustrated as mounted adjacent the liquid accumulating vessel it is apparent that it could be located at some distance therefrom, in which case the conductors 18 and 14 would be extended to locate the separator 11 at a distance from the liquid accumulating vessel.

From the foregoing it will be seen that this invention is one well adapted to attain all of the ends and objects hereinabove set forth together with other advantages which are obvious and are inherent to the structure.

It will be understood that certain features and subcombinations are of utility and may be employed without reference to other features and subcombinations. This is contemplated by and is within the scope of the claims.

As many possible embodiments may be made of the invention without departing from the scope thereof, it is to be understood that all matter herein set forth or shown in the accompanying drawings is to be interpreted as illustrative and not in a limiting sense.

Having described the invention, I claim:

1. A liquid knockout apparatus for removing liquid from a high pressure fluid flow line including, a liquid-accumulating vessel communicating with and suspended at a single point of support from the high pressure fluid line for receiving liquid which has been separated from the line, a discharge valve for controlling the discharge of liquid from said vessel, said vessel being supported in a normal position with the weight of the vessel and its contents unequally distributed on opposite sides of its point of support, a control unit also supported by the fluid line and engaged by the exterior of the vessel at a point spaced from the point of support of said vessel whereby a portion of the weight of the vessel is applied to said unit, and means in the control unit responsive to the force applied by the weight of the accumulating vessel for effecting a balance of such force, variations in the weight of said vessel and its contents due to changes in the weight of the liquid therein resulting in variations in the force applied to the control unit, and means for actuating the discharge valve of the vessel in accordance with the force applied to the control unit.

2. A liquid knockout apparatus as set forth in claim 1, together with means for returning a portion of the liquid from the vessel back into the flow line.

3. A liquid knockout apparatus as set forth in claim 1, wherein the discharge valve is pressure-actuated, means for supplying an operating pres-

sure to said discharge valve, and means actuated by said control unit for controlling the application of pressure through the pressure supply means to the discharge valve, whereby operation of said discharge valve is actually controlled by the control unit.

4. A liquid knockout apparatus for removing liquid from a high pressure fluid flow line including, a liquid-accumulating vessel communicating with the high pressure line for receiving liquid which has been separated from the line, a discharge valve for controlling the discharge of liquid from said vessel, means for attaching and suspending one end of the vessel to the flow line so that the flow line supports a portion of the weight of the vessel, and its contents, a control unit engaged by the vessel at a point spaced from the point of attachment of the vessel with the flow line for also supporting a portion of the weight of the vessel and its contents, and a support for the control unit secured to the flow line, whereby said control unit and vessel are carried by the flow line, and means in the control unit responsive to changes in the force applied to the control unit by variations in weight of the vessel and its contents for controlling operation of the discharge valve.

5. A liquid knockout apparatus as set forth in claim 4 together with means for conducting a portion of the liquid which accumulates in the vessel back into the flow line.

6. A liquid knockout apparatus including, a high pressure flow line for conducting high pressure fluid from a well, means for mounting a liquid accumulating vessel in communication with the flow line in a position below said line for receiving liquids from said line, a discharge valve for controlling the discharge of liquid from the lower end of the vessel, means actuated by deflection of the mounting of the vessel as caused by the weight of the vessel and its contents for controlling the operation of the discharge valve, and a conductor having its lower end communicating with the upper portion of the vessel and having its upper end terminating in the same plane as and communicating with the flow line, said flow line having a vertical portion adjacent the conductor, whereby when the liquid from the vessel rises upwardly in the conductor and said liquid enters the flow line, the flowing fluid stream in said line will carry said liquid upwardly in said vertical portion and then through the flow line beyond said vertical portion.

7. A liquid knockout apparatus for removing liquid from a high pressure fluid flow line wherein the fluid contains hydrocarbon liquid and water, said apparatus including a liquid-accumulating vessel communicating with and suspended at a single point of support from the high pressure flow line for receiving liquid which has been separated from the line, a pressure-actuated discharge valve for controlling the discharge of liquid from said vessel, said vessel being supported in a normal position with the weight of the vessel and its contents unequally distributed on opposite sides of its point of support, a control unit also supported by the fluid line and engaged by the exterior of the vessel at a point spaced from the point of support of said vessel whereby a portion of the weight of the vessel is applied to said unit, means in the control unit responsive to the force applied by the weight of the accumulating vessel for effecting a balance of such force, variations in the weight of said vessel and its contents due to changes in the weight of the liquid therein resulting in variations in the force applied to the control unit, and means for actuating the discharge valve of the vessel in accordance with the force applied to the control unit.

ing in variations in the force applied to the control unit, means for supplying an operating pressure to said pressure-actuated discharge valve, means operated by said control unit for controlling the application of pressure through the pressure supply means to the discharge valve, whereby operation of said discharge valve is actually controlled by the control unit, and a conductor establishing communication between the upper portion of the liquid-accumulating vessel and the flow line, whereby hydrocarbon liquid accumulated in the vessel will be returned to the flow line.

8. A liquid knockout apparatus as set forth in claim 7, together with means utilizing the flowing fluid stream in the flow line for drawing the hydrocarbon liquid which accumulates in the vessel back into the flow line.

9. A liquid knockout apparatus including, a high pressure fluid flow line having a downwardly disposed offset portion therein, a closed liquid-accumulating vessel in a plane below the flow line, a conductor extending from a point upstream of the offset portion of the flow line to the vessel for conducting liquids separated from the flow line to said vessel, a second conductor having its lower end communicating with the vessel and its upper end connected with the offset portion of the flow line, whereby when the liquid level rises within the second conductor and enters said offset portion the flowing fluid stream within the flow line functions to draw said liquid back into said flow line, the two conductors forming the sole support for the liquid-accumulating vessel and being secured to the vessel at one end thereof, whereby the opposite end of said vessel will undergo movement caused by the variations in weight of said vessel due to changes in quantity of liquids therein, a discharge valve for controlling the discharge of liquid from the lower portion of the vessel, and means actuated by the movement of the vessel as caused by variations in weight of the vessel and its contents for operating said discharge valve.

10. A liquid knockout apparatus including, a high pressure fluid flow line having a downwardly disposed offset portion therein, a closed liquid-accumulating vessel in a plane below the flow line, a conductor extending from a point upstream of the offset portion of the flow line to the vessel for conducting liquids separated from the flow line to said vessel, a second conductor having its lower end communicating with the vessel and its upper end connected with the offset portion of the flow line, whereby when the liquid level rises within the second conductor and enters said offset portion the flowing fluid stream within the flow line functions to draw said liquid back

into said flow line, the two conductors forming the sole support for the liquid-accumulating vessel and being secured to the vessel at one end thereof, whereby the opposite end of said vessel will undergo movement caused by the variations in weight of said vessel due to changes in quantity of liquids therein, a discharge valve for controlling the discharge of liquid from the lower portion of the vessel, a control unit engaged by the unsupported end of the vessel and responsive to weight changes in the vessel for operating the discharge valve, and a support for said control unit extending from and secured to the flow line.

11. A liquid knockout apparatus including, a high pressure flow line for conducting high pressure fluid from a well, means for mounting a liquid accumulating vessel in communication with the flow line in a position below said line for receiving liquids from said line, a discharge valve for controlling the discharge of liquid from the lower end of the vessel, means actuated by deflection of the mounting of the vessel as caused by the weight of the vessel and its contents for controlling the operation of the discharge valve, and a conductor having its lower end communicating with the upper portion of the vessel and having its upper end terminating in the same plane as and communicating with the flow line, said flow line having a vertical portion adjacent the conductor, whereby when the liquid from the vessel rises upwardly in the conductor and said liquid enters the flow line, the flowing fluid stream in said line will carry said liquid upwardly in said vertical portion and then through the flow line beyond said vertical portion, said discharge valve being pressure-actuated, and means for supplying operating pressure to said discharge valve from the high pressure flow line.
